UNITED STATES PATENT OFFICE

2,518,316

CONTROL FOR REFRIGERATED TRUCKS

Charles F. Henney, Dayton, Ohio, assignor to
General Motors Corporation, Dayton, Ohio, a
corporation of Delaware

Application March 23, 1946, Serial No. 656,754

7 Claims. (Cl. 62—4)

1

This invention relates to refrigerating apparatus and more particularly to an improved arrangement for refrigerating trucks and the like.

One object of this invention is to provide an improved arrangement for supplying power for operating a refrigerant compressor.

Another object of this invention is to provide an improved control arrangement for the compressor operating mechanism.

Still another object of this invention is to provide a refrigerating system capable of refrigerating a plurality of storage compartments each requiring a different temperature.

A still further object of this invention is to provide an improved arrangement for providing stand-by operation.

A further object of this invention is to provide a system in which power from a common source is utilized for operating both the refrigerant compressor and the air circulating means and in which means is provided for automatically discontinuing operation of the compressor without discontinuing the operation of the air circulating means.

Further advantages of the present invention will be apparent from the following description, reference being had to the accompanying drawings, wherein a preferred form of the present invention is clearly shown.

In the drawings:

Fig. 1 shows an elevational view of a refrigerated truck embodying my invention;

Fig. 2 diagrammatically shows the power transmitting mechanism and the refrigeration circuit;

Fig. 3 diagrammatically shows a slightly modified power transmitting mechanism;

Fig. 4 is a fragmentary vertical sectional view taken on line 4—4 of Fig. 5 showing a modified air distributing arrangement for use within a refrigerated truck;

Fig. 5 is a horizontal sectional view taken substantially on line 5—5 of Fig. 4;

Fig. 6 is a fragmentary sectional view taken substantially on line 6—6 of Fig. 5; and

Fig. 7 is a fragmentary vertical sectional view taken substantially on line 7—7 of Fig. 6.

Referring now to Fig. 1 of the drawing, there is shown a refrigerated truck having a storage compartment 10, driver's cab section 12, an engine compartment 14, and an air conditioning housing 16 which, for purposes of illustration, has been shown mounted directly beneath the storage compartment 10. Within the housing 16 there is mounted a refrigerant compressor 18

2

connected to a drive shaft 20 through a centrifugal clutch 22 of the type which serves to de-clutch the compressor 18 when the speed of the shaft 20 falls below a given speed and to connect the compressor 18 to shaft 20 when the speed of the shaft increases above a predetermined speed.

The shaft 20 may be operated either by the hydraulic motor 24 or the stand-by electric motor 26. The rotor of a condenser blower 28 is directly mounted on the shaft 20 and serves to circulate outside air into the housing 16 through the inlet 30 and to blow the air over the condenser 32 located directly within the air outlet opening 34 provided in the wall of the housing 16 as shown. The rotor of an evaporator blower 36 is also mounted directly on the shaft 20 and serves to circulate air to be conditioned in thermal exchange with the refrigerant evaporator 38. The inlet duct 40 of the evaporator blower 36 is connected to the return air inlet 42 disposed adjacent the floor of the storage compartment 10 as shown in Fig. 1.

In the construction shown in Fig. 1, the air leaving the evaporator 38 is discharged upwardly through the air distributing duct 44 which leads to the conditioned air distributor 46 arranged adjacent the ceiling of the storage compartment 10. The arrangement of the air inlets and air outlets within the compartment 10 may be varied considerably without departing from the spirit of my invention.

The compressor 18 discharges compressed refrigerant into the condenser 32 through the refrigerant line 50. Condensed refrigerant leaves the condenser 32 through the liquid line 52 within which there is provided a conventional refrigerant flow control device 54 which may be a thermostatic expansion valve, a fixed restrictor, or any other type of control device. The vaporized refrigerant leaves the evaporator 38 through the low pressure vapor line 56 which leads to the compressor 18.

The hydraulic pump 60 is adapted to be driven by the main truck engine 62 by means of the belt 64 or any equivalent power transmitting mechanism. A manually operated clutch 66 is provided whereby the pump 60 may be declutched from the engine 62 at will. Reference numeral 68 designates a conventional clutch operating lever for operating the clutch 66. The hydraulic motor 24 and hydraulic pump 60 are both shown somewhat diagrammatically since the construction and operation of such elements are well-known to those skilled in the art of hydraulic

piston power transmitting devices. The detailed construction of motor 24 and pump 60 may, for example, be similar to the structure shown and described in the Thomas B. Doe Patent No. 2,241,701 dated May 13, 1941. These hydraulic elements 24 and 60 are generally similar to one another and differ only in the arrangement employed to change the angularity of the wobble or guide plates 84 and 72 thereof. However, tilting of the wobble or guide plate of such elements to change its angularity relative to the drive shaft thereof in order to vary the stroke of the pistons and consequently the volume of fluid pumped thereby is also conventional and well-known to those skilled in the art. For example, such an arrangement is shown and described in the Milton E. Hanson Patent No. 2,104,696 dated January 4, 1938.

In the present disclosure the pump 60 is of the type adapted to deliver a constant volume of liquid to motor 24 irrespective of changes in speed of the main engine 62. The stroke controlling wobble or guide plate 72 of pump 60 is connected to the drive shaft 70 thereof by means of a conventional universal connection indicated at 74. Pump 60 is provided with a speed responsive fly ball governor device 76 which has an arm 71 secured to a portion of the device 76 surrounding and being movable longitudinally along shaft 70. The bent end part of arm 71 may bear against or be attached to a box or ring indicated at 73 and within which the wobble or guide plate 72 rotates. The fly ball governor 76 operates in response to the speed of the pump shaft 70 and moves the arm 71 longitudinally along shaft 70 and this arm tilts the box or ring 73 to vary the angular relationship of plate 72 relative to the shaft for changing the stroke of each of the pistons 90. Thus when the engine 62 attains sufficient speed to render the fly ball governor 76 effective this governor by virtue of changing the stroke of pistons 90, increases or decreases the volume of fluid delivered per revolution of the pump shaft 70 to cause the output of pump 60 to remain constant.

In order to vary the speed of the compressor 18 so as to balance the output of the compressor with the refrigeration demand or load, I have provided a thermostatically operated means for varying the speed of the hydraulic motor 24. This thermostatic means comprises a closed fluid system including an expandable and contractible member such as a bellows 80 or the like, a bulb 82 and a tube connection therebetween. A control rod 81 has its one end attached to a movable portion of bellows 80 and extends to the interior of motor 24. The thermostat bulb 82 may be mounted directly within the storage compartment 10 or at any other convenient location where it will be affected by changes in the refrigeration requirements of the refrigerating system. The end of rod 81 located within motor 24 is connected to an arm 85 secured to a box or ring indicated at 87 and within which a wobble or guide plate 84 rotates as is disclosed in the aforementioned Hanson patent. Guide plate 84 is connected to the drive shaft 86 of motor 24 by any suitable or conventional universal joint similar to the manner in which guide plate 72 of pump 60 is connected to shaft 70. Changes in temperature within storage compartment 10 of the truck, to which bulb 82 is exposed, will cause the fluid within the thermostatic system to expand and/or condense and this action of the fluid expands and/or contracts the

bellows 80. Consequently rod 81 secured to the movable portion of bellows member 80 will be moved. Movement of rod 81 shifts arm 85 and consequently box or ring 87 to which it is secured is tilted to thereby change the angular relationship of guide plate 84 relative to shaft 86. Changes in the angularity of wobble or guide plate 84 increases or decreases the stroke of the piston 90 of motor 24 and consequently the speed of the motor. The guide plates 72 and 84 are each connected to four pistons 90 which are uniformly spaced about the central shaft in the conventional manner. Hydraulic fluid is discharged from the pump 60 through the line 92 which leads to the motor 24 and the fluid leaving the motor 24 returns to the pump 60 through the return line 94. The construction and the principle of operation of hydraulic motors and pumps of this general type are now well known and need no further description.

Power is transmitted from the motor driven shaft 86 to the shaft 20 by means of the belt 100. A centrifugal clutch 102 is provided for de-clutching the shaft 20 from the hydraulic motor shaft 86 when it is desired to stop the hydraulic motor 24 and to supply stand-by power by means of the electric motor 26. This stand-by operation is provided so as to make it possible to refrigerate the storage compartment of the truck when the truck is standing still at the warehouse or at any other location where there is electric power available for operating the motor 26 and it is desired not to operate the truck engine 62. It is to be understood that clutch 22 may cause the compressor 18 to be intermittently stopped and/or started in response to the speed of the hydraulic motor 24 and consequently shaft 20 while the blowers 28 and 36 operate continuously with operation of motor 24 and shaft 20 to circulate air over the condenser 32 and evaporator 38 irrespective of whether or not compressor 18 is operating.

In Fig. 3 I have shown a slightly modified arrangement which may be substituted for the arrangement shown in Fig. 2. Like reference numerals have been used to designate like parts in Figs. 2 and 3. The two arrangements are similar in many respects and both contemplate the use of a hydraulic power transmission. The hydraulic pump 120 shown in Fig. 3 is a conventional pump, the output of which varies in accordance with the driving speed which in this case would vary with the speed of the engine 62. A bypass 122 has been provided between the pump outlet line 124 and the pump inlet 126 and a pressure regulating valve 128 has been provided in the bypass line which serves to compensate for changes in the speed of the pump 120. The valve 128 serves to maintain a substantially constant pressure differential between the fluid in the outlet line 124 and the fluid in the inlet line 126. A conventional accumulator 130 has been provided in the line 124.

A second bypass 132 has been provided, as shown in Fig. 3, in which there is provided a valve 134 which is controlled by the thermostat 136 located in the conditioned space. As the demand for refrigeration decreases the thermostat 136 serves to open the by-pass valve 134 with the result that less fluid is supplied to the fluid motor 138 which drives the compressor and the blowers. This decrease in fluid causes the motor 138 to operate slower with the result that when no refrigeration is required the speed of the motor will have decreased to a point where the clutch 22 will

declutch the compressor. The centrifugal clutches 22 and 102 shown in Fig. 3 serve the same purpose as the correspondingly numbered clutches serve in the arrangement shown in Fig. 2. Thus the motor 138 will operate the blowers at a reduced speed after the thermostat indicates that no more refrigeration is required and after the clutch 22 has disengaged the compressor. A slightly different arrangement of blowers has been shown in Fig. 3. Rather than mounting the rotors of the blowers 28 and 36 directly on the shaft 20, as in Fig. 2, they have been mounted on a separate shaft 139 and are adapted to be driven through the belt 140. The blowers 28 and 36 in this modified showing also operate to circulate air over the condenser 32 and evaporator 38 irrespective of whether or not the clutch 22 drivingly connects compressor 18 to shaft 20.

In Figs. 4, 5, 6, and 7 I have shown a modified storage compartment arrangement for use within the truck body 10. Whereas Fig. 1 shows a general duty truck having a single storage compartment; Figs. 4 through 7 show a special duty delivery truck having three separate compartments 150, 152 and 154 arranged to be maintained at different temperatures. The compartment 150 is a non-insulated, non-refrigerated compartment which is accessible through the rear door 156. This compartment may be used for transporting goods which do not require refrigeration. Reference numeral 152 designates a central insulated, low temperature food compartment within which there are provided hollow shelves 158 for supporting frozen foods or the like. The hollow shelves 158 allow the refrigerated air to circulate therethrough even though the compartment 152 is completely filled with frozen foods or the like. Refrigerated air passes from the main air supply duct 159 into the rear duct 160 which has been provided along the back wall of the compartment 152 and from there the air flows through the hollow shelves 158 and into the two corner ducts 162 provided as shown in Figs. 4 and 5. The air flows from the corner ducts 162 into the air space 170 formed above the compartment 154 and returns to the inlet of the evaporator fan through the air passage 172 formed in the side wall of compartment 154 and from thence returns to the evaporator through the passage 175 provided in the floor of the truck. Baffles 174 in the passage 172 improve the air distribution therein. The top and side wall of the compartment 154 are refrigerated in this manner and serve to cool the air in the compartment 154.

The compartment 154 is accessible through the front door 164 whereas the center compartment 152 is accessible from the compartment 154 through the inner door 166. The lining 167 of the compartment 154 is made of metal and is preferably spaced and insulated from the outer metal wall of the truck body so as to facilitate transfer of heat from the cool air in passage 172 to all portions of the interior of compartment 154.

The same type of refrigeration apparatus may be used for cooling the multiple compartment truck shown in Figs. 4 through 7 as is used cooling the single compartment truck shown in Fig. 1. The refrigeration systems disclosed herein are designed for use in refrigerating either type of truck.

In order to control the temperature within the low temperature compartment 152, the refrigeration control thermostat 82 of the system shown

in Fig. 2 or the thermostat 136 of the refrigeration system shown in Fig. 3 would be placed within the compartment 152 so as to maintain that compartment at the desired temperature. The temperature within the compartment 154 may be controlled by providing a plurality of baffles 180 along the side wall 176 which may be used for covering a portion of the wall 176 at such times when the temperature in the compartment 154 tends to fall below the desired temperature. The baffles 180 are pivotally mounted by means of a series of stationary mounting lugs 182 and are connected together by the main operating rod 184 so as to operate in unison. The operating rod 184 is controlled by the expansible bellows 186 which in turn is controlled by the thermostat 190 located within the compartment 154. The baffles 180 are preferably formed of insulating material so as to better prevent the transfer of heat from the wall 176 to the air within the compartment 154 when the baffles are moved against the wall.

While no means has been shown for controlling the operation of the stand-by motors 26, it is obvious that these motors may be controlled either manually or automatically so as to maintain suitable temperatures within the refrigerated compartments during stand-by operation.

While the form of embodiment of the invention as herein disclosed, constitutes a preferred form, it is to be understood that other forms might be adopted, as may come within the scope of the claims which follow.

What is claimed is as follows:

1. In combination, a vehicle having means forming a food storage compartment therein and a closed refrigerating system carried thereby, a prime mover for driving said vehicle, a hydraulic pump operated by said prime mover, means for maintaining the output of said pump substantially constant, a variable speed hydraulic motor operatively connected to said pump, said refrigerating system including a compressor, a condenser and an evaporator for cooling said food storage compartment, torque transmitting means between said motor and said compressor, and means operable in response to temperatures within said food compartment and acting directly on said hydraulic motor for varying the speed of operation thereof in accordance with refrigeration requirements of said evaporator.

2. In combination, a vehicle having means forming a food storage compartment therein and a closed refrigerating system carried thereby, a prime mover for driving said vehicle, a hydraulic pump operated by said prime mover, means for maintaining the output of said pump substantially constant, a variable speed hydraulic motor operatively connected to said pump, said refrigerating system including a compressor, a condenser and an evaporator for cooling said food storage compartment, torque transmitting means between said motor and said compressor, means operable in response to temperatures within said food compartment for varying the speed of operation of said hydraulic motor, and means actuated automatically in response to the speed of said hydraulic motor for starting and/or stopping operation of said compressor.

3. In combination, a vehicle having means forming a food storage compartment therein and a closed refrigerating system carried thereby, a prime mover for driving said vehicle, a hydraulic pump operated by said prime mover, means for

maintaining the output of said pump substantially constant, a variable speed hydraulic motor operatively connected to said pump, said refrigerating system including a compressor, a condenser element and an evaporator element for cooling said food compartment, means for circulating air over one of said elements, torque transmitting means drivingly connecting said air circulating means and said compressor to said hydraulic motor, means operable in response to temperatures within said food compartment for varying the speed of operation of said hydraulic motor, and means independent of said air circulating means actuated automatically in response to the speed of said hydraulic motor for starting and/or stopping operation of said compressor.

4. In combination, a vehicle having means forming a food storage compartment therein and a closed refrigerating system carried thereby, a prime mover for driving said vehicle, a hydraulic pump operated by said prime mover, means for maintaining the output of said pump substantially constant, a variable speed hydraulic motor operatively connected to said pump, said refrigerating system including a compressor, a condenser element and an evaporator element for cooling said food compartment, means for circulating air over said condenser element, means for circulating air over said evaporator element, torque transmitting means drivingly connecting both of said air circulating means and said compressor to said hydraulic motor, means operable in response to temperatures within said food compartment for varying the speed of operation of said hydraulic motor, and means independent of both of said air circulating means actuated automatically in response to the speed of said hydraulic motor for making and/or breaking the driving connection between said motor and said compressor.

5. In combination, a vehicle having means forming a food storage compartment therein and a closed refrigerating system carried thereby, a prime mover for driving said vehicle, a hydraulic pump operated by said prime mover, means for maintaining the output of said pump substantially constant, a variable speed hydraulic motor operatively connected to said pump, said refrigerating system including a compressor, a condenser and an evaporator for cooling said food storage compartment, blower means for circulating air over said evaporator and into said food compartment, torque transmitting means drivingly connecting said blower means and said compressor to said hydraulic motor, and means operable in response to temperatures within said food compartment acting directly on said hydraulic motor for varying the speed of operation thereof whereby the speed of operation of said compressor and said blower means is changed in accordance with refrigeration requirements of said evaporator.

6. In combination, a vehicle having means

5 forming a food storage compartment therein and a closed refrigerating system carried thereby, a prime mover for driving said vehicle, a hydraulic pump operated by said prime mover, means for maintaining the output of said pump substantially constant, a variable speed hydraulic motor operatively connected to said pump, said refrigerating system including a compressor, a condenser and an evaporator for cooling said food storage compartment, blower means for circulating air over said evaporator and into said food compartment, blower means for circulating air over said condenser, torque transmitting means drivingly connecting said blower means and said compressor to said hydraulic motor, and means operable in response to temperatures within said food compartment acting directly on said hydraulic motor for varying the speed of operation thereof whereby the speed of operation of both of said blower means and said compressor is changed in accordance with refrigeration requirements of said evaporator.

7. In combination, a vehicle having means forming a food storage compartment therein and a closed refrigerating system carried thereby, a prime mover for driving said vehicle, a hydraulic pump operated by said prime mover, means for maintaining the output of said pump substantially constant, a variable speed hydraulic motor operatively connected to said pump, said refrigerating system including a compressor, a condenser and an evaporator for cooling said food storage compartment, torque transmitting means between said motor and said compressor, means operable in response to temperatures within said food compartment for controlling the stroke of said hydraulic motor to vary its speed of operation in accordance with refrigeration requirements of said evaporator, and means actuated automatically in response to the speed of said hydraulic motor for making and/or breaking the driving connection between said motor and said compressor.
